UNITED STATES PATENT OFFICE

167,717

AWNING

Roy B. Price, Cincinnati, Ohio

Application March 8, 1951, Serial No. 14,435

Term of patent 14 years

(Cl. D21—6)

To all whom it may concern:

Be it known that I, Roy B. Price, a citizen of the United States, residing at Cincinnati, Hamilton County, and State of Ohio, have invented a new, original, and ornamental Design for an Awning, of which the following is a specification, reference being had to the accompanying drawings, forming a part thereof, wherein:

Fig. 1 is a top plan view of an awning, showing my new design;

Fig. 2 is an end elevational view thereof;

Fig. 3 is a perspective view thereof; and

Fig. 4 is a fragmentary top plan view thereof, to an enlarged scale.

I claim:

The ornamental design for an awning, as shown.

ROY B. PRICE.
